UNITED STATES PATENT OFFICE.

PAUL VON VAGO AND JOSEPH PALDY, OF BUDAPEST, HUNGARY, ASSIGNORS TO VAGO.
PALDY G. M. B. H., OF BERLIN, GERMANY, A CORPORATION OF GERMANY.

SECURING TOGETHER OF SHEETS OF PAPER.

Application filed April 12, 1924, Serial No. 706,044, and in Hungary April 28, 1923.

This invention relates to a method of and means for binding together sheets of paper. More particularly, it relates to a method of joining or binding sheets of paper together 5 along a line by exerting pressure upon the superposed sheets, and means for performing such compressive and binding action.

The object of our invention is to bring the superposed sheets of paper into such proximity that the sheets will adhere to each other without the use of any adhesives, metal clamps, or other binders. The binding action is applied along a line formed in the surface of the paper, which may be in the form 10 of letters, newspapers, bags and other articles. It is also possible to utilize our invention in securing sheets of paper together in book form, and in sealing together newspapers to prevent the unauthorized opening 15 thereof. In this manner the misuse of the papers, usual by newspaper sellers, in selling to the public copies of papers which have already been opened, is prevented.

Our invention may also be used for securing 20 together files and other documents, for closing envelopes, or for the production of paper bags and the like.

In the accompanying drawings are shown, by way of example, various arrangements for carrying out the present invention.

Fig. 1 shows an elevation of a machine capable of being mounted on a table and operated by hand, and provided with resiliently mounted pressure rollers.

Fig. 2 shows a vertical cross section of the machine of Fig. 1.

Fig. 3 shows an elevation of a modification of the machine shown in Fig. 1.

Fig. 4 shows a modification of the roller teeth.

Figs. 5 and 6 are views of several types of bearings for resiliently mounting the rollers.

It is well known that wrappers, newspapers, letter-paper, tubes for cigarettes, and other paper articles can be bound together by folding over the edges and providing them with corrugations. In such a method, however, the corrugations serve to stiffen the folded edges in such a way as will prevent the fold from opening.

We have found that a high degree of adhesion can be obtained between the sheets of paper bound together by use of cooperating toothed members provided with wedge

shaped teeth for stretching and pressing the sheets together along a line. In accordance with our invention, sheets of paper are passed between sharp wedge shaped teeth provided on two interengaging wheels held together under pressure. One of these wheels, for example 1 (Fig. 1), may be driven, while the other wheel 2 is rotated by the teeth of the first wheel, as is described later.

The pitch, which is the same for both wheels, and the dimensions of the teeth should preferably be large in comparison to the thickness of the paper to be bound together; for example, the pitch of the teeth may be about 1-2 mm.

By means of sufficient tension, the separate sheets are pulled along and exposed to high pressure along the binding seam. In this manner the fibres of the separate sheets are stretched and brought into such intimate contact with the fibres of adjacent sheets, by means of the pressure exerted on the binding seam, that when the pressure ceases the sheets are held together and cannot be separated without tearing and destroying the fibers of the material. This binding action is exerted along a line at some distance inward from the edge because the binding effect is then greater. By reason of the wedge shaped construction of the teeth it is possible to allow the entire pressure available in the device to act upon a small surface, namely the sharp edge of the teeth or the sharp edge of the tooth spaces, so that a very high specific pressure is obtained. By means of this method the sheets numbering anywhere from two to about thirty can be effectively bound together. Such binding is effected without the use of adhesives or auxiliary devices such as staples, fasteners and the like. Even though the fibres of the paper have been stretched, the binding along the seam is extremely effective and permanent.

The method of binding sheets of paper together by means of interengaging members with sharp wedge shaped teeth may be used alone or in combination with folding actions.

In conjunction with the method described for binding superposed sheets of paper together by means of members provided with tooth-like projections, a high degree of binding action can be obtained for paper pads of varying thickness and character without changing the adjustment of the machine by

utilizing a modification of our invention wherein the binding members provided with tooth-like projections are resiliently mounted with respect to each other.

5 This point is of importance since it has been found by investigations that the binding action of the sheets of paper is dependent upon the use of certain specific pressures varying with the thickness, the quality, and 10 number of sheets to be bound together. If the working pressure is below this specific pressure no adhesion will take place between the sheets of paper while at a higher pressure the paper will be torn. By resiliently arranging 15 the toothed rollers so that they can yield with respect to each other, a self-regulating and self-adjusting of the binding pressure may be obtained that eliminates the necessity of changing the machine adjustment 20 for paper of varying character, thickness and number of sheets.

A machine provided with means for resiliently pressing the binding members together is shown in Figs. 1 and 2. A pair of wheels 1 and 2 serve to longitudinally guide the sheets and at the same time bind them together along a line at a distance inward from the edge. The teeth are preferably sharp and of wedge shape with sharp wedge shaped 30 tooth spaces between them. But our invention is not restricted to machines of this particular tooth form for other forms of teeth may be employed within the scope of our invention.

35 In operation a crank 26 drives the lower wheel 1 keyed to the shaft 23. As the teeth of the wheels 1 and 2 engage, the driven wheel 1 will rotate the wheel 2 which is loosely mounted on its shaft 27. In order to 40 enable the device to be used for letters and sheets of different kinds of paper, or for paper of different thicknesses or pads of a different number of sheets, the wheels have their centres adjustable in the direction of 45 the line passing through their centres.

In the device shown in Figs. 1 and 2, the shaft 27 is mounted on an eccentric disc 80 which in turn is pivoted on the eccentric shaft 24. By means of the blade spring lever 29 bearing against a fixed point 45 of the framework 25, the wheel 2 is pressed against the wheel 1. Between the two wheels there is a slot 44 in the operating table 33 which is preferably arranged in or near the common tangential plane of the wheels. The fixed point or stop 45 of the framework 25, against which the blade spring 29 bears, can be adjusted by means of the set screw 28 to vary the spring pressure. The blade spring 29 may be secured in a slot in the shaft 24 or to a pivot provided thereon.

By means of its base 30, the frame 25 is capable of being secured to the top of a table or other support.

65 For guiding the paper pad in the direction

of the arrow 31 a work table 33 is secured to a projection 32 on the frame 25 or forms a portion of the frame. The table is provided with an upwardly bent edge 34 to form a guide parallel to the direction of movement of the paper. As an aid in guiding the paper in a straight line along said table a member may be employed for pressing the paper against the table before it enters between the rollers. Such action may be effected by a 70 blade spring 35, as shown in Figs. 1 and 3.

75 Further modifications of the invention are shown in Figs. 3 to 6. In the arrangement shown in Figs. 1 and 2, the wheels, after their position has once been adjusted by the 80 set screw may for a large range of thicknesses or number of sheets, remain in that position—apart from the shifting of one or other of the wheels according to the thickness of the sheets inserted between them. It may be desirable under some conditions, or in such instances where the thickness of the paper or the number of the sheets to be bound together over a large range, to retain without adjustment the specific pressure which causes the 85 sheets to bind together. This may be obtained, for example, by employing a series of co-operating springs of different character, for instance consisting of a blade spring 29 and a spiral spring 291, as shown in Fig. 3, 90 the first of these springs being fixed to the pivot 24, and the last being fixed to a portion of the frame.

95 In the construction illustrated in Fig. 4 the wheels are not provided with straight teeth but with spiral teeth. By this means the length of the sharp edges of the teeth, which produces the binding action between the paper sheets, can be increased without changing the width of the wheels.

100 In the modification shown in Fig. 5, the wheel 1 is pressed against the wheel 2 mounted in the guide 38 and slidably therein under the action of a spring 39. In the modification shown in Fig. 6, resiliency is obtained by 105 using a double-lever, blade 41 bearing near one end against the abutment 42 and at the other end against a set screw or adjustable spring 43; the blade 41 may be in the form of a blade spring. A forked-bearing 40 carrying the wheel 2 is mounted on the free end of 41 in such a manner that the spring lever-action presses the wheel 2 against wheel 1 which is mounted in a manner similar to 110 wheel 2 in Fig. 1.

115 It is to be understood that various modifications may be made in the details of construction as here illustrated and described without departing from the scope of our invention as defined by the following claims.

Having thus described our invention what we claim as new and desire to secure by Letters Patent is:—

1. In a device for binding superposed 120 sheets of paper together, a frame, two interen-

- gaging wheels mounted thereon, the wheels having toothlike projections and correspondingly shaped tooth spaces thereon and acting with pressure upon the superposed sheets to cause them to adhere to each other along a line, means for rotating one of said wheels, and lever means for resiliently pressing the wheels towards one another.
2. In a device for binding superposed sheets of paper together, a frame, two interengaging wheels mounted thereon, the wheels having toothlike projections and correspondingly shaped tooth spaces thereon and acting with pressure upon the superposed sheets to cause them to adhere to each other along a line, means for rotating one of said wheels, a pivot loosely mounted within said frame, an eccentric on said pivot, said other wheel mounted loosely on said eccentric, and means comprising a series of cooperating springs of different characters fixed at one end to said pivot and acting thereon, and fixed at the other end to a portion of said frame.
- 5 6. In a device for binding superposed sheets of paper together by means of interengaging members having toothlike projections acting with pressure upon the superposed sheets to cause them to adhere to each other along a line, means for driving one of said members, the said members being adapted to yield radially in relation to each other, and a table disposed adjacent to the interengaging surfaces of said members, said table being adapted to guide the superposed sheets of paper between said members.
- 10 7. In a device for binding superposed sheets of paper together by means of interengaging members having toothlike projections acting with pressure upon the superposed sheets to cause them to adhere to each other along a line, means for driving one of said members, a table disposed adjacent to the interengaging surfaces of said members, said table being adapted to guide the superposed sheets of paper between said members, and a spring actuated member on said table, said spring actuated member being adapted to press the sheets of paper against said table.
- 15 8. In a device for binding superposed sheets of paper together, two interengaging members having toothlike projections and correspondingly shaped tooth spaces thereon, means for actuating said members and means for resiliently pressing the said members together, the said toothed members being adapted to act upon the superposed sheets of paper to cause them to adhere to each other along a line.
- 20 9. In a device for binding superposed sheets of paper together, a frame, two interengaging members mounted thereon, the members having toothlike projections and correspondingly shaped tooth spaces thereon, means for actuating one of said members and means for resiliently pressing the members together, said members being adapted to act upon the superposed sheets of paper to cause them to adhere to each other along a line.
- 25 10. In a device for binding superposed sheets of paper together by means of interengaging members having toothlike projections acting with pressure upon the superposed sheets to cause them to adhere to each other along a line, means for driving one of said members and a table disposed adjacent to the interengaging surfaces of said mem-
- 30 3. In a device for binding superposed sheets of paper together, a frame, two interengaging wheels mounted thereon, the wheels having toothlike projections and correspondingly shaped tooth spaces thereon and acting with pressure upon the superposed sheets to cause them to adhere to each other along a line, means for rotating one of said wheels, a pivot loosely mounted within said frame, an eccentric on said pivot, said other wheel mounted loosely on said eccentric, a blade spring fixed at one end to said pivot and acting thereon and a stop on the frame adapted to act on the other end of said blade spring, said blade spring being adapted for swinging said pivot and thus pressing the wheels together.
- 35 4. In a device for binding superposed sheets of paper together, a frame, two interengaging wheels mounted thereon, the wheels having toothlike projections and correspondingly shaped tooth spaces thereon and acting with pressure upon the superposed sheets to cause them to adhere to each other along a line, means for rotating one of said wheels, a pivot loosely mounted within said frame, an eccentric on said pivot, said other wheel mounted loosely on said eccentric spring means for swinging said eccentric around said pivot, said spring means being fixed at one end to said pivot and acting thereon, a stop on the frame, said spring means bearing at its other end against said stop and a stop screw for adjusting the pressure of said spring means.
- 40 5. In a device for binding superposed sheets of paper together, a frame, two interengaging wheels mounted thereon, the wheels having toothlike projections and correspondingly shaped tooth spaces thereon and acting with pressure upon the super-
- 45 50 55 60 65 70 75 80 85 90 95 100 105 110 115 120 125 130

bers said table being adapted to guide the superposed sheets of paper between said members.

11. In a device for binding superposed sheets of paper together by means of interengaging members having toothlike projections acting with pressure upon the superposed sheets to cause them to adhere to each other along a line, means for driving one of said members, the said member being adapted to yield radially in relation to each member, a table disposed adjacent to the interengaging surfaces of said members, said table being adapted to guide the superposed sheets of paper between said members and a member of said table, said member being adapted to press the sheets of paper against said table.

12. In a device for binding superposed sheets of paper together, two interengaging members having toothlike projections and correspondingly shaped tooth spaces thereon said projections and said toothspaces being of sharp wedge-shaped form, means for ac-

tuating said members and means for pressing the said members together, the said wedge-shaped tooth members being adapted to act upon the superposed sheets of paper to cause them to adhere to each other along a line.

13. In a device for binding superposed sheets of paper together by means of interengaging members having tooth-like projections acting with pressure upon the superposed sheets to cause them to adhere to each other along a line, means for driving one of said members, a table disposed adjacent to the interengaging surfaces of said members, said table being adapted to guide the superposed sheets of paper between said members, and a member on said table, said member being adapted to press the sheets of paper against said table.

In testimony whereof we affix our signatures.

PAUL VON VÁGÓ.
JOSEPH PÁLDY.
